US00D519925S

(12) **United States Design Patent** (10) **Patent No.:** **US D519,925 S**
Milan (45) **Date of Patent:** **** May 2, 2006**

(54) **HOUSING FOR COMPUTER CABLE CONNECTOR**
(76) Inventor: **Henry Milan**, 1709 Apple Ridge Ct.,
Rochester Hills, MI (US) 48306
(**) Term: **14 Years**
(21) Appl. No.: **29/203,747**
(22) Filed: **Apr. 19, 2004**
(51) **LOC (8) Cl. 13-03**
(52) **U.S. Cl. D13/133; D13/147**
(58) **Field of Classification Search** D13/133,

(57) **CLAIM**

The ornamental design for a housing for computer cable connector, as shown and described.

DESCRIPTION

FIG. 1 is a top plan view of a housing for a computer cable connector of the present invention;
FIG. 2 is a bottom plan view thereof;
FIG. 3 is a front elevation view thereof;
FIG. 4 is a rear elevation view thereof;
FIG. 5 is a right side elevation view thereof; and,
FIG. 6 is a left side elevation view thereof.

The broken line showing of the environment is for illustrative purposes only and forms no part of the claimed design.
